(57)

CLAIM

The ornamental design for a vehicle filter oil, as shown and described.

DESCRIPTION

1. Vehicle filter oil

1.1 : Perspective

1.2 : Top

1.3 : Bottom

1.4 : Front

1.5 : Left

(Continued)

1.6 : Right**1.7** : Back**1.8** : Perspective

A vehicle filter oil for hydraulic circuits.

Broken lines are used to show boundaries of the vehicle filter oil that form no part of the claimed design.

1 Claim, 8 Drawing Sheets
